UNITED STATES PATENT OFFICE

ADIEL Y. DODGE, OF SOUTH BEND, INDIANA

LIGHTING UNIT

Application filed January 10, 1929. Serial No. 331,614.

5 My invention relates to electric lamps.

One of the objects of my invention is to improve the light distribution of electric lamps of the type comprising a transparent bulb and a filament housed in said bulb.

10 A further object of my invention is to improve the light distribution of electric bulbs used in connection with concave reflectors as in headlight construction.

15 Further objects will appear from the description and claim.

In the drawings, in which an embodiment of my invention is shown,—

15 Figure 1 is an axial section through a parabolic reflector showing the bulb in position;

Fig. 2 is an enlarged view of the bulb shown in Fig. 1;

20 Fig. 3 is a side view of the bulb, part being broken away to show the axial vertical section;

Fig. 4 is a front view of the bulb; and

Fig. 5 is a bottom view of the bulb.

25 Referring to the drawings in detail, the construction shown thereon comprises a parabolic reflector 1 and an electric lamp 2 mounted therein with the light center 3 at or near the focus of the parabola so that the light rays A from the source falling on the reflector are reflected therefrom in substantially parallel rays B to give a concentrated beam. The lamp base 4 and its connection with the socket portion 5 of the reflector may be of any usual or suitable construction.

35 In certain installations such as headlights for automobiles the axis of the lamp may be horizontal, and in such installations there is usually a large proportion of the light from the filament which escapes forwardly through the open front of the reflector which serves very little useful purpose and which, in fact, is often harmful in that it causes a disagreeable and dangerous glare, and decreases the visibility of the driver.

40 In order to make use of this light, which is

otherwise practically waste, and avoid this disagreeable and dangerous glare, the glass enclosing bulb 6 is provided at its forward end with a lens formation 7 of sufficient extent to intercept substantially all of the light rays from the light source which do not fall on the main parabolic reflector 1 and which lie above a horizontal plane through the light source. This lens may be so designed as to lessen the divergence of the rays falling thereon so as to cause them to emerge in a substantially horizontal direction and so as to materially lessen the lateral divergence as shown at C in Figures 1 and 2. As the rays lying below the horizontal plane through the light source are not in a direction to cause glare and are in a direction to be useful, the lower edge 8 of the lens is so designed as to lie substantially in a horizontally plane through the light source so that the rays below this plane are not diverted. As shown in Fig. 4, the lens is semi-circular in shape, with its upper semi-circular edge lying substantially in the surface of a cone having its center at the light source and its base defined by the circumference of the opening in the concave reflector, as indicated at D in Fig. 1.

45 While I have described but one embodiment of my invention, it is obvious that many modifications therein may occur to those skilled in the art, and I desire, therefore, that my invention be limited only by the scope of the appended claim and by the prior art.

I claim:

50 A light projecting apparatus comprising a concave reflector and an electric lamp in front of said concave reflector, said lamp comprising a transparent bulb and a concentrated light source in said bulb, said bulb having a lens integral therewith for lessening the divergence of the rays from the light source falling thereon, said lens projecting forwardly from the front of the bulb and having a convex front face above the horizontal plane.

through the light source and having a lower crescent shaped surface lying substantially in said horizontal plane, said lens having a greater refractive power vertically than horizontally whereby the upward rays striking the lens are refracted to a substantially horizontal direction while the laterally directed rays still diverge after being refracted.

In witness whereof, I have hereunto sub-
10 scribed my name.

ADIEL Y. DODGE.
